UNITED STATES PATENT OFFICE.

CLARK S. COMSTOCK, OF BLOOMFIELD, NEW JERSEY.

LOOP.

No. 867,949.

Specification of Letters Patent.

Patented Oct. 15, 1907.

Application filed January 17, 1907. Serial No. 352,739.

To all whom it may concern:

Be it known that I, CLARK S. COMSTOCK, a citizen of the United States, and a resident of Bloomfield, in the county of Essex and State of New Jersey, have made 5 and invented certain new and useful Improvements in Loops, of which the following is a specification.

My invention relates to an improvement in wire loops, such for instance as those employed on the ends of suspenders, shoulder straps, on overalls, garters, etc., 10 and adapted to engage with a button or stud secured to the article or garment.

The object of the invention is to provide a loop made of a single piece of wire, easily and readily bent, and completely finished by an automatic wire bending 15 machine, whereby the time, labor and cost of assembling two or more pieces or parts, such as is now necessary in case of those loops ordinarily used, may be saved.

A further object of the invention is to so construct 20 the loop that it may be employed with buttons or studs formed with different size hubs, and with no danger of becoming accidentally disengaged therefrom when in use, and with these and other ends in view, consists of a loop constructed of a single piece of wire bent to form 25 an upper cross bar for attachment to the end of the strap, suspender or garter, two depending converging arms, one being bent to form a lower rigid loop for the reception and retention of the button or stud, said lower loop having its free end loosely engaging the 30 lower free end of the other arm, as hereinafter described and set out in the claims.

In the accompanying drawings, Figure 1 is a view in front elevation of my improved loop, showing the same attached to the end of a suspender or strap, and in engagement with a button or stud. Fig. 2 is a sectional view taken on the line 2—2 of Fig. 1. Fig. 3 is a view in front elevation of the loop detached from the strap. Fig. 4 is a similar view of a modification.

Referring to the drawings, A represents the end of a 40 strap, suspender or garter, and B a part of any garment with which the loop may be employed and to which is secured the button or stud C. The loop is made of a single piece of wire, and in order to permit of its attachment to the strap A, it is formed with the cross bar 45 D, from one end of which latter depends the arm E, having the free outwardly bent end F.

From the opposite end of the bar D depends the arm G, the two arms E—G converging to form the restricted throat H through which must pass the hub of the button 50 or stud C, and which restriction prevents the loop from becoming accidentally disengaged from the button when in use. The lower end of the arm G is bent outwardly as at A then downwardly forming the retaining loop I, then upwardly, and at its extreme end into the

eye K, through which latter extends the free horizontal 55 end F of the arm E, as shown in Figs. 1, 3 and 4.

When in its normal position, the end F of the arm E projects sufficiently far through the eye K to prevent disengagement therefrom, and when the button or stud passes between the arms E—G, accidental disengagement is impossible, as the arms are forced outwardly and the end F still further projected through the eye K. By thus forming and locking the free ends of the wire, it is possible to completely form the loop at one operation of the automatic machine (not shown), but 65 if desired, the free end F of the arm E may also be bent into the form of an eye as illustrated in Fig. 4. In such instance, however, a second operation of the machine becomes necessary to finish the loop.

As the button passes through the throat H, the arms 70 are forced outwardly, permitting the button to be received and retained in the lower rigid loop I, as illustrated in Fig. 1, the arms returning to their normal positions as shown in Figs. 1 and 3 and preventing accidental disengagement of the button and loop. By 75 a slight upward push upon the button, it is forced through the throat H and into the upper widened portion of the loop, whereupon it may be easily and readily disengaged therefrom.

From the foregoing it will be understood that my 80 improved loop is exceedingly simple and economical to manufacture, as by being made of a single piece of wire, no assembling of parts or pieces is necessary, and a great saving in time, labor and money thereby effected. At the same time, it is adapted for any size 85 button or stud, and may be employed for all purposes for which similar loops are used.

Having fully described my invention, what I claim 90 as new and desire to secure by Letters Patent, is:—

1. A loop of the character described constructed of a single piece of wire and formed with an upper cross bar and two depending converging arms, one of said arms having a free end, the other of said arms being formed into a lower retaining loop and having an eye formed at its end which loosely engages the free end of said first 95 mentioned arm, substantially as described.

2. A loop of the character described constructed of a single piece of wire and formed with an upper cross bar and two depending converging arms, one arm having a free end, the other arm being formed into a retaining loop 100 and having an eye formed at its end which loosely engages the free end of said first mentioned arm, the upper cross bar, the retaining loop and the arms being in the same vertical plane, substantially as described.

Signed at New York, borough of Manhattan, in the 105 county of New York, and State of New York, this 16th day of January, A. D. 1907.

CLARK S. COMSTOCK.
